United States Patent Office

Des. 203,185

Patented Dec. 14, 1965

203,185

MEMO CLIP ATTACHMENT FOR A TELEPHONE OR SIMILAR ARTICLE

Norbert Leopoldi, 4180 Marine Drive, Chicago, Ill.

Filed Mar. 27, 1964, Ser. No. 79,222

Term of patent 14 years

(Cl. D26—14)

The ornamental design for a memo clip attachment for a telephone or similar article, substantially as shown.
